UNITED STATES PATENT OFFICE

165,774

BRIDGE TALLY

Vernon Martin, Paris, Ontario, Canada, assignor
to The Walker Press Limited, Paris, Ontario,
Canada, a company of Ontario

Application February 13, 1950, Serial No. 7,919

Term of patent 14 years

(Cl. D34—13)

To all whom it may concern:

Be it known that I, Vernon Martin, a subject of the Dominion of Canada, residing at Paris, in the Province of Ontario, Dominion of Canada, have invented a new, original, and ornamental Design for a Bridge Tally, of which the following is a specification, reference being had to the accompanying drawing, forming a part hereof.

Figure 1 is a view of the inside of a bridge tally, showing my new design; and

Figure 2 is a perspective view of one-half of the outside thereof when folded on the two score lines shown in Figure 1.

The appearance of the other half of the outside thereof, not shown, is conventional.

The drawing is lined to indicate color contrast.

I claim:

The ornamental design for a bridge tally, as shown and described.

VERNON MARTIN.
